DESIGN FOR A SPECTACLE FRAME OR SIMILAR ARTICLE

Stefan Kaesz, New York, N. Y.

Application December 6, 1943, Serial No. 111,933

Term of patent 7 years

To all whom it may concern:

Be it known that I, Stefan Kaesz, a citizen of no country, residing at 1120 Brighton Beach Avenue, in the city of New York, county of Kings, and State of New York, have invented a new, original, and ornamental Design for a Spectacle Frame or Similar Article, of which the following is a specification, reference being had to the accompanying drawing, forming part thereof.

In the drawing

Fig. 1 is a plan view of the spectacle frame or similar article, showing my new design; and Fig. 2 is a front view of the spectacle frame shown in Fig. 1.

I claim:

The ornamental design for a spectacle frame or similar article, as shown.

STEFAN KAESZ.
